(57) **CLAIM**

The ornamental design for a water can, as shown and described.

DESCRIPTION

The file of this patent contains at least one drawing/photograph executed in color. Copies of this patent with color drawing(s)/photograph(s) will be provided by the Office upon request and payment of the necessary fee.

1. Water can
2. Water can
3. Water can
- 1.1 : Back
- 1.2 : Left
- 1.3 : Front
- 1.4 : Right
- 1.5 : Bottom
- 1.6 : Top
- 1.7 : Perspective
- 2.1 : Back
- 2.2 : Left
- 2.3 : Front
- 2.4 : Right
- 2.5 : Bottom
- 2.6 : Top
- 2.7 : Perspective
- 3.1 : Back
- 3.2 : Left
- 3.3 : Front
- 3.4 Top

The area encompassed by the dot-dash boundary line in Figure 1.5 forms no part of the claimed design.

The broken lines in Figure 2.5 represent portions of the water can in which the design is embodied that form no part of the claimed design.
